UNITED STATES PATENT OFFICE.

ROBERT SUCZEK, OF PHILADELPHIA, PENNSYLVANIA, ASSIGNOR TO C. H. WHEELER
MANUFACTURING COMPANY, OF PHILADELPHIA, PENNSYLVANIA, A CORPORATION
OF PENNSYLVANIA.

CONDENSING APPARATUS.

1,273,948.

Specification of Letters Patent. Patented July 30, 1918.

Original application filed March 8, 1917, Serial No. 153,454. Divided and this application filed October 11, 1917. Serial No. 198,904.

To all whom it may concern:

Be it known that I, ROBERT SUCZEK, a subject of the Emperor of Austria-Hungary, residing in the city of Philadelphia, 5 county of Philadelphia, and State of Pennsylvania, have invented certain new and useful Improvements in Condensing Apparatus, of which the following is a specification.

- 10 My invention relates to jet condenser apparatus wherein, as well understood in the art, cooling water comes into direct contact with the steam or other vapor which is to be condensed.
- 15 In such apparatus it is common to employ a centrifugal pump for removing all the liquid, comprising both the injection cooling water and the condensed vapor or steam, the pump generally being submerged 20 in the water in the bottom of the apparatus. Such a removal pump removes not only the water referred to, but also considerable air existent in the injection water and in part the air entering the condenser with the 25 steam. In association with such apparatus it is common also to employ an air pump of any suitable type for removing air or uncondensable gases to maintain a vacuum higher than would be possible by the 30 employment of the removal pump alone.

It is the object of my invention to cause the removal pump to remove a greater proportion of the air and thereby reduce the amount of air to be removed by the air pump. 35 To this end I provide one or more ducts, conduits or pipes communicating with the suction inlet of the propeller of the centrifugal pump and extending into the liquid collecting chamber of the condenser to a 40 point well above the level of the liquid therein.

For an illustration of one of the various forms my invention may take, reference is to be had to the accompanying drawing.

45 Referring to the drawing, J is the body of the jet condenser which receives through the opening E the steam or other vapor to be condensed. Surrounding the body J is the water distributing chamber C receiving 50 the cooling or injection water through the connection W. In the wall of the body J is formed a series of nozzles or openings N through which the cooling water is in-

jected into contact with the steam entering at E. The steam in contact with the 55 cooling water is condensed into water, and the injection water and condensate fall through the cone, guide passage or diffuser D into the bottom of the body J, where it rises to a level maintained above the upper 60 most level of the suction of the submerged impeller I of the centrifugal removal pump P. The impeller I is driven by the shaft S rotating in bearings B and driven by 65 any suitable motor, as a steam turbine or electric motor, not shown. The impeller I discharges into the volute discharge casting V, which delivers to any suitable point outside of the apparatus.

Within the body J are provided the tubes, 70 ducts or air conduits T extending above the variable liquid level A and communicating at their upper ends preferably above the lower end of member D with the air space 75 within the condenser and at their lower ends being deflected laterally at L and delivering at K into the suction orifices of and on opposite sides of the impeller I.

Extending into the lateral tubes L to a point approximate their orifices K are the 80 pipes P² terminating in the nozzles P¹.

Communicating with the air space of the condenser is an opening O connecting through the pipe Q with an air removing pump G of any type, as an entrainment 85 pump, an ejector, or the like.

The operation is as follows:

The impeller I by its rotation, as well understood in the art, withdraws water from the bottom of the body J and delivers 90 it into the volute or discharge casting V, from which it is delivered to any suitable point exterior to the apparatus.

This water has entrained therein air originally entering with the injection water and 95 some of the air entering the condenser with the steam to be condensed.

More air may be removed, however, by use of the conduits or tubes T as indicated, in which case the impeller suction will draw 100 air from the air space of the condenser through the tubes T, thereby producing or assisting in producing a vacuum in the condenser, and the air will pass into the impeller I with the water and be removed 105 therewith. By this action more air is re-

moved, and there is accordingly less load upon the air removing device G connected with the pipe Q.

The amount of air removed by the pump 5 P may be further increased by delivering through the nozzles P¹, P¹ any suitable motive fluid, as water, or an elastic motive fluid, as steam, under any suitable pressure. The action of the nozzles P¹ is to cause an 10 augmented suction through the tubes T and so cause the impeller I to remove still more of the air.

This application is a division from my application Serial Number 153,454, filed 15 March 8, 1917.

What I claim is:

1. The combination with a jet condenser, of a centrifugal pump impeller submerged by the water therein for removing said 20 water, means for removing elastic fluid from said condenser, and auxiliary means for removing elastic fluid comprising a duct for conducting elastic fluid from the space above the level of said water to the suction of said 25 impeller.

2. The combination with a jet condenser, of a centrifugal pump impeller submerged by the water therein for removing said water, means for removing elastic fluid from said 30 condenser, and a duct for conducting elastic fluid from the space above the level of said water to a region at the highest level of the inlet of said impeller.

3. The combination with a jet condenser, 35 of a centrifugal pump impeller submerged by the water therein for removing said water, means for removing elastic fluid from said condenser, means forming a passage for conducting elastic fluid from the space above 40 the level of said water to the suction of said impeller, and means delivering motive fluid into said passage.

4. The combination with a jet condenser, of a centrifugal pump impeller submerged 45 by the water therein for removing said water, means for removing elastic fluid from said condenser, means forming a passage for conducting elastic fluid from the space above the level of said water to the suction of said 50 impeller, and a nozzle delivering motive fluid into said passage near its delivery into said impeller.

5. The combination with a jet condenser,

of a centrifugal pump impeller submerged by the water therein, means for removing 55 elastic fluid from said condenser, auxiliary elastic fluid removing means comprising a duct for conducting the elastic fluid from the space above the level of said water to the suction of said impeller, and means delivering motive fluid into said passage near its delivery into said impeller.

6. The combination with a jet condenser having a diffuser discharging into a liquid collecting chamber, of a centrifugal pump 65 impeller submerged by the water collected in said chamber, means for removing elastic fluid from said condenser, and a duct communicating with the suction of said impeller and extending above the level of said water 70 to a point above the lower end of said diffuser.

7. The combination with a jet condenser, of a centrifugal pump having a double suction impeller, said impeller submerged by 75 the water in said condenser, means for removing elastic fluid from said condenser, and ducts communicating with the suction inlets of said impeller and with the space above the level of said water within said 80 condenser.

8. The combination with a jet condenser, of a centrifugal pump having an impeller, the suction of said impeller receiving the 85 water from said condenser for removing the same, and means wholly within the body of said condenser forming a duct, delivering into said suction of said impeller and communicating with the space above the level 90 of the water within said condenser.

9. The combination with a jet condenser, of a centrifugal pump having an impeller, the suction of said impeller receiving the water from said condenser for removing the same, means wholly within the body of said 95 condenser forming a duct delivering into said suction of said impeller and communicating with the space above the level of the water within said condenser, and a motive fluid nozzle discharging adjacent the discharge of said duct in the suction of said impeller.

In testimony whereof I have hereunto affixed my signature this 9th day of October, 1917.

ROBERT SUCZEK.
